UNITED STATES PATENT OFFICE.

JOHN F. BAKER, OF MANSFIELD, OHIO, ASSIGNOR TO WESTINGHOUSE ELECTRIC & MANUFACTURING COMPANY, A CORPORATION OF PENNSYLVANIA.

ROTARY FURNACE.

Application filed July 27, 1926. Serial No. 125,143.

My invention relates to furnaces and particularly to rotary furnaces having means for automatically effecting the periodic discharge of heat-treated material therefrom.

5 An object of my invention is to provide an efficient discharge means for a furnace.

Another object of my invention is to provide in a furnace having a conveyor carrying pivoted hearth trays, and a rotatable 10 cam means for periodically and successively 15 cam means for periodically and successively tilting said trays to cause the discharge of material therefrom.

Other objects of my invention will be apparent from the disclosure.

15 In practicing my invention according to the present embodiment, a power-driven rotary conveyor having pivoted-hearth-trays thereon is provided in cooperative relation with a heat-treating furnace, similar to the 20 rotary furnace shown in my co-pending application Serial No. 117937 filed June 23, 1926. A power-driven rotatable cam is provided for periodically and successively 25 engaging the trays to tilt them and effect the discharge of heat-treated material therefrom. A means, similar to that shown in the above-mentioned application, is provided to control the operation of the cam in accordance with the movement of the conveyor.

In the drawings, Fig. 1 is a vertical sectional view of a rotary furnace showing my cam tilting means operatively connected thereto.

35 Fig. 2 is a horizontal section of one half of the furnace.

Referring to the drawings, a preferably annular rotary furnace 10 is provided with an annular chamber 11 and has an outer 40 casing 13 and inner walls of refractory insulating material 15. Suitable heating means are provided in said chamber, such heating means being here shown as electric heating elements 18 that are electrically connected to a suitable source of energy (not shown).

An annular runway 20 is provided in the bottom portion of the furnace. The upper portion of the runway opens into the annular chamber 11.

50 An annular column 27 is vertically positioned in the runway and is so supported on the rim 22 of a wheel 23, as to be moved through the runway upon rotation of the

wheel 23. The upper end of the annular column has a hearth-supporting member 26 that may be integral therewith. A hearth tray 27 is mounted on each hearth-supporting member and is connected to the member by a pivoted joint, located at the outer edges of the hearth tray and its supporting member, the inner edge of the tray being free and extending over the edge of the supporting member. The hearth tray is adapted to receive material to be heat- treated.

Sealing means for the runway 20 are preferably provided at the bottom of the furnace and comprise concentric channel members 29 and 30 secured to the furnace near the runway and having such circular space between them as to permit the passage of the columns 21 therebetween. An inverted annular channel member 31 is secured to the columns and is adapted to be 75 immersed in sand or other suitable material that is placed in the channel members 29 and 30.

The wheel 23 is rotatably mounted on a central bearing 32 and has its rim 22 resting on a plurality of roller members 33. For the purpose of driving the wheel 23 a circular rack 35 is secured to the wheel and meshes with a gear wheel 36 that is mounted on a shaft 37. The shaft 37 is rotatably 80 mounted in a pair of journal members 38. A worm gear wheel 40 is also secured to the shaft 37 and meshes with a worm screw 41 that is operatively connected to a hearth motor 42 or other suitable prime mover. 90 The hearth motor 42 is, of course, connected to a suitable source of electrical energy.

A discharge outlet 44 is connected to the furnace and has its outer end immersed in oil or other quenching medium in the tank 95 45. The outlet 44 is adapted to receive heat-treated material that is discharged from the hearth trays.

An automatic means for effecting a discharge of material from the hearth tray comprises a cam 47 that is eccentrically secured to a shaft 48, mounted in a suitable bearing 49 in the furnace walls. The cam is normally in position shown in Fig. 1 and is so located in the chamber 11 opposite to the discharge outlet 44 as to be in position to engage the free end of a hearth tray 27 when the tray arrives opposite to the dis-

charge outlet 44. It will be seen that, when the tray is in this position and the cam 47 is rotating, the tray will be tilted about its pivoted joint to permit the material on the tray to be discharged through the outlet 44.

A power driven means to rotate the cam 47 is provided and comprises a worm wheel 51 that is keyed to the shaft 48 and meshes with a worm screw 52 that is secured to a vertical shaft 54. The vertical shaft 54 is mounted in suitable bearing members 55 and 56. At the upper end of the shaft 54, a worm screw 58 is connected and is adapted to mesh with a worm wheel 59 that is secured to the shaft 60 of a tilting motor or other prime mover 61, the tilting motor being electrically connected to a suitable source of energy.

Means are provided to so periodically energize the motor 61 as to effect the movement of the cam 47 when successive hearth trays arrive opposite the discharge outlet 44, to cause a tilting of the hearth tray. A convenient form of such means is the commutator member 64 that is similar to the commutator member described in my co-pending application above mentioned. The commutator member 64 is secured to the upper end of a shaft 65 that is mounted in bearings 66 and 67 and is so secured, at its lower end, to the hub of the wheel 23 that it will be rotated when the wheel rotates.

Commutator member 64 comprises a metallic annular member 69 that is suitably insulated from the shaft and is provided with a plurality of integral projections 70. The number of these projections is the same as the number of hearth trays. Insulating material 71 is provided between adjacent projections 70 and has its outer surface flush with the outer end of the projections 70. A brush 72 is insulatedly mounted on the furnace structure above the commutator 64 and is in electrical engagement with the annular member 69 of the commutator member 64 at all times. A second brush member 74 is insulatedly mounted on the furnace structure and is adapted to engage the periphery of the commutator member 64. The brushes 72 and 74 are electrically connected to the tilting-motor circuit.

When the hearth motor is started, it is apparent that it will cause the wheel 23 to rotate, and the columns 21 and hearth trays 27 will be caused to move in a circular path. The projections 70 are so positioned as to first engage the brush 74 when the corresponding hearth trays arrive opposite the discharge outlet 44. When the brush 74 engages a projection 70, the circuit through the motor 61 will be closed, and the motor 61 will start and cause the rotation of the cam 47. The cam 47 will, of course, tilt the hearth tray that is opposite the discharge outlet 44, as heretofore described, thus causing

the discharge of heat treated material from the hearth tray 27. The continued rotation of the cam 47 will permit the tray 27 to return to its original position.

The projections 70 are of such width as to permit the energization of the motor 61 for only the length of time necessary to permit the cam to return to its lowermost position as shown in Fig. 1. The cam may be made circular to prevent any interference with the passage of a hearth tray 27 thereover, even though the cam 47 does not return to its exact original position. Preferably, there is a slight clearance between the cam and a tray passing over it.

80

While, in this embodiment of my invention, the conveyor is adapted to move continuously, by suitable means, such as the control system shown in my above-mentioned copending application, intermittent operation of the hearth motor may be provided to permit alternate operation of the hearth motor and the tilting motor. It will, of course, be obvious, that my tilting mechanism may be applied to furnaces in which the conveying means is not rotary.

85

While I have shown and described, for purposes of illustration, a particular form of my invention, it may, of course, be employed in other forms without departing from the spirit and scope thereof, as set forth in the appended claims.

90

I claim as my invention:

1. In a furnace, in combination, a conveyor, means for driving said conveyor, a hearth tray pivotally mounted on the conveyor, and rotatable means positioned below the normal level of the hearth tray for engaging said tray to effect the discharge of material therefrom.

105

2. In a furnace, in combination, a conveyor, means for continuously driving said conveyor, a hearth tray pivotally mounted on the conveyor, rotatable means positioned below the normal level of the hearth tray for periodically tilting said tray to effect the discharge of material therefrom, and means for controlling the operation of said rotatable means.

110

3. In a furnace, in combination, a conveyor, means for driving said conveyor, a plurality of hearth trays pivotally mounted thereon, a rotatable cam positioned below the normal level of the hearth trays and adapted to periodically and successively engage said trays to tilt the same and effect the discharge of material therefrom, power-driven means for operating the cam, and control means for periodically causing the operation of said power-driven means.

120

4. In a furnace, in combination, a conveyor, means for driving said conveyor, a plurality of hearth trays pivotally mounted thereon, a rotatable cam positioned below the normal level of the hearth trays and

130

adapted to periodically and successively engage said trays to tilt the same to effect the discharge of material therefrom, power-driven means for operating the cam, and electric means controlled by said conveyor for periodically causing the operation of said power-driven means, said electric means being adapted to maintain said power-driven means in operation for a predetermined interval of time. ¹⁰
In testimony whereof, I have hereunto subscribed my name this 13th day of July, 1926.

JOHN F. BAKER.
